INK APPLYING INSTRUMENT

Bernard J. Swanson, Fort Wayne, Ind.

Application August 1, 1947, Serial No. 765,382

3 Claims. (Cl. 15—134)

1

This invention relates to improvements in an ink applying instrument for marking goods displayed for sale or on shipping cases to indicate price or destination.

Ordinarily, instruments having an ink reservoir for applying ink to surfaces where indicia is required are susceptible to leakage and become unusable, especially when left unused for a protracted period, or become incapacitated because of drying of the wick through which ink from the reservoir is intended to exude.

An object of the instant invention is to afford a structure having an ink reservoir, a stopper for confining ink therein provided with a wick and an opening through which ink from the reservoir is supplied to the wick, and a cap for enclosing the stopper and sealing the connection between the stopper and reservoir when the instrument is out of use, thus to obviate leakage and maintain the instrument in operative condition in readiness for use.

And another object of the invention is to provide an ink-applying instrument of simple construction having few parts that are easily disassembled and cleansed.

Other objects and advantages of the invention appear in the following description.

An illustrative embodiment of the invention is shown in the accompanying drawings, in which:

Fig. 1 is an elevational view of a structure in which the invention is incorporated, portions thereof being in section;

Fig. 2 is another elevational view drawn to an enlarged scale of the stopper containing a wick, a part being in section; and

Fig. 3 is a fragmentary elevational view drawn to an enlarged scale showing the connection between the reservoir, stopper and cap assembly.

The illustrative embodiment of the invention consists of a barrel 4, constituting a reservoir for ink, one end of which is closed and tapered, the opposite end thereof being open and provided with an externally threaded thin annular flange 5, there being an annular shoulder 6 formed at the base of said flange. A stopper 7 is provided which extends into the open end of the barrel and has threaded engagement therein. The stopper 7 has an exterior collar 8 that fits snugly into the flange 5, there being a gasket 9 interposed between the shoulder 6 and the collar 8.

The upper end of the stopper has a concentric socket 10 in which is disposed a snugly fitting wick 11, and a feed duct 12 is made in the stopper affording communication between the reservoir

and the socket. The bore of the stopper through the socket is of greater diameter than through the duct and is tapered at the juncture of the socket and duct, thus forming an annular seat 13 for the lower end of the wick which bears with more or less force thereon and tends to vary the flow of ink through the wick.

A cap 14 is provided which is preferably tapered and closed at one end, and the opposite end has a threadless sleeve 15 that snugly fits around the corresponding end of the barrel 4 when in closed position. The bore of an intermediate portion 16 of the cap, adjacent the sleeve, is slightly tapered inwardly toward the closed end of the cap and is interiorly threaded to engage the exteriorly threaded flange 5, so that when the cap is screwed into place on the barrel, the flange thereupon becomes clamped snugly around the collar 8, thus establishing a tight fit between the barrel and stopper, and the cap is hermetically sealed thus preventing evaporation of the ink and consequent drying of the wick.

The lower tapered end of the barrel is preferably shaped to snugly fit within the cap and is frictionally held therein without threaded engagement with the cap. The cap when thus disposed affords balance to the instrument while in use and avoids loss of the cap through inadvertence. Preferably, a pocket clip 17 of usual construction is attached to the cap by which to avert loss of the instrument when carried about.

Operation

The instrument is prepared for use by removing the cap and the stopper from the barrel and supplying a quantity of ink to the reservoir. The stopper is then replaced, tightened against the gasket, and the cap screwed in place to enclose the stopper and its wick, which tightens the flange of the barrel about the collar 8 on the stopper, thus affecting a complete hermetical seal with respect to the barrel, the stopper and the cap. When the parts are thus assembled, the instrument may be carried around with impunity without danger of leakage of ink or drying of the wick.

When the instrument is placed in service the cap is removed and replaced onto the closed end of the barrel where it is frictionally held. The instrument then is inverted, whereupon the wick becomes saturated with ink passing from the reservoir through the feed duct 12, and the exposed end of the wick then is applied to the goods or packages to be marked.

Ink removed from the wick during the writ-

ing operation is replaced automatically from the supply in the reservoir by capillary attraction through the feed duct, so the wick is kept saturated and in readiness for use. The wick initially fits firmly in the socket, and when saturated with ink becomes swollen to an extent causing its lower end to rest upon the seat 13 in the stopper. In this manner the outflow of ink from the reservoir is retarded and flooding of the ink through the wick thus is prevented.

As the saturation of the wick is lessened by use of the instrument, pressure of the lower end of the wick upon the seat is relieved, thus permitting replenishment with ink through the feed duct from the reservoir.

Variations from the particular construction above disclosed may be resorted to by the exercise of skill in the art, without departure from the invention.

What I claim is:

1. An ink-applying instrument consisting of a barrel, constituting an ink reservoir, one end of which is closed, the opposite end of which is externally and internally threaded and provided with an annular shoulder and an axially extending thin flange adjacent said shoulder, a stopper threaded in said barrel provided with an annular collar seated on the shoulder and snugly fitting in said flange, the upper end of said stopper having a concentric socket communicating with said reservoir through a feed duct, an annular tapered seat located at the juncture of said socket and feed duct, a wick disposed in said socket contacting said seat, one end of said wick projecting beyond the corresponding end of said stopper affording a nib, and an unvented cap the open end of which is internally tapered and threaded for engaging the

external threads of said flange and barrel and provided with an axially extending threadless sleeve fitting around an adjacent smooth portion of said barrel when the cap is in place.

5 2. An ink-applying instrument having an ink reservoir consisting of a barrel one end of which is internally and externally threaded and provided with an axially extending flange, a stopper engaged by the internal threads of the barrel, having a socket containing a wick protruding therefrom, a duct through which ink from the reservoir passes to the wick, and a collar fitting within said flange, and a cap for enclosing the wick and clamping the flange about said collar, 10 said cap having a tapered internally threaded portion engaging the external threads of the barrel.

15 3. The structure as defined in claim 2, and a threadless sleeve portion fitting around a corresponding threadless portion of the barrel.
